(57) **CLAIM**

The ornamental design for a wheel or wheel cover, as shown and described.

DESCRIPTION

This application contains subject matter related to the following co-pending U.S. design patent application:

Application Ser. No. 29/410,672, filed herewith and entitled "Wheel or Wheel Cover".

FIG. 1 is a front view of a wheel or wheel cover according to my design; and,

FIG. 2 is a perspective view thereof.

The broken line showing of the rear of the wheel and the central hub area is included for the purpose of illustrating environment and forms no part of the claimed design.

1 Claim, 1 Drawing Sheet

FIG. 1

FIG. 2
